UNITED STATES PATENT OFFICE.

ISIDOR KITSEE, OF PHILADELPHIA, PENNSYLVANIA, ASSIGNOR TO CHARLES E. WILSON, OF SAME PLACE.

COMMUNICATING SYSTEM.

SPECIFICATION forming part of Letters Patent No. 666,883, dated January 29, 1901.

Application filed February 20, 1896. Serial No. 580,050. (No model.)

To all whom it may concern:

Be it known that I, ISIDOR KITSEE, of the city and county of Philadelphia, State of Pennsylvania, have invented certain new and 5 useful Improvements in Electric Communications, of which the following is a specification.

My invention relates to telephonic circuits.

The object of my invention is to use a telephonic circuit for telegraphic communications simultaneously with the sending of telegraphic messages over the same circuit.

Repeated experiments have established the fact that if a metallic circuit at the terminals 15 of which telephonic instruments are inserted is grounded between the terminals with the intervention of one or more condensers the telephonic communications between the two terminals are not interfered with. On the 20 contrary such insertion and grounding of the condensers has beneficial effect upon the condition of the line. Again, if alternating currents of high frequency (no matter how low their intensity) are sent over a line-wire the 25 intervention of condensers will only intensify the action upon another condenser if employed as a receiver. Experiments have also demonstrated the practicability of simultaneously using part of the telephonic line 30 grounded through condensers for certain telegraphic communications without interfering with the telephonic messages, or vice versa.

Referring now to the drawings, Figures 1 and 2 are electrical diagrams of telephonic 35 circuits embodying my invention.

In Fig. 1 wires 1 and 2 are the circuits connecting telephonic stations A and A' with each other. The station A is provided with the telephonic receiver a, and the station A' 40 is provided with the similar instruments a'. Between these two telephonic stations are the two telegraphic stations T and T', similar parts of these stations being designated by similar letters, with the exception that the 45 parts of station T' are also provided with the numeral 1. H and H' are condensers connected at places more or less remote from stations A and A' to line-wire 2. In series with these condensers are the coils E and E' 50 and the keys D and D', the lower parts of

which are connected through switches S and S' to sources of current X and X' or to ground, the opposite terminals of the sources of current being also connected to ground. The sources of currents have to be rapidly alternating or recurring. At the sending-station 55 the operator manipulates his key in the usual manner; but it has to be understood that each closing of the key does not only send one impulse over the line, but a series of such 60 impulses, the flow time of which corresponds with the closing of the key, a dot with its short closing time sending impulses over the line for a shorter period than a dash with its longer closing time. These impulses travel 65 over the line-wire and the coil inserted in the line at the receiving-station. As around the coils E and E', sending as well as receiving 70 station, the condensers B and B', respectively, are shunted, it follows that as each multitude 75 of impulses induces one continuous whistling sound in such condensers the operator at the receiving-station will be enabled to distinguish between the difference of characters—dots or dashes—through the shorter or longer 80 duration of this sound.

Speaking of Fig. 2, the line-wire 2 is not in electrical connection with the primary coils E or E', but is connected with the secondary coils F and F', which coils have in their proximity the tertiary coils G and G'. In this method the impulses which flow through the localized primary coil E are translated with the aid of the secondary coil connected to the line-wire into impulses of the desired intensity, and these so-transmitted impulses 85 may then be translated with the aid of the tertiary coil into impulses of the necessary intensity if a condenser should be used as a receiver. 90

I prefer the employment of a secondary coil connected to the line-wire, because it obviates the difficulty of battery or dynamo connections, and it also allows the translation of the impulses to be sent to any required intensity. Where the condenser is employed as receiver, the third coil is only necessary for the purpose of raising the electromotive force of the transmitted electrical impulses for such a combination of apparatus. 95

Having now described my invention, what I claim as new, and desire to secure by Letters Patent, is—

In a system of telephonic communications, 5 one or more sending and one or more receiving stations, connected together with a metallic circuit, in combination with a local source of an electric current of rapidly recurring or alternating impulses, connected 10 through one terminal with the ground and

through the other terminal, with the interpolation of a sending-key and condenser, to the telephonic circuit.

In testimony whereof I sign my name, this 17th day of February, 1896, in the presence 15 of two subscribing witnesses.

ISIDOR KITSEE.
